US0D1030595S

(12) **United States Design Patent** (10) **Patent No.:** **US D1,030,595 S**
(45) **Date of Patent:** **** Jun. 11, 2024**

(54) **LIFTGATE PART FOR MOTOR VEHICLE**

(71) Applicant: **Dr. Ing. h.c. F. Porsche**
Aktiengesellschaft, Stuttgart (DE)

(72) Inventor: **Shuichi Yamashita**, Stuttgart (DE)

(73) Assignee: **Dr. Ing. h.c. F. Porsche**
Aktiengesellschaft (DE)

(**) Term: **15 Years**

(21) Appl. No.: **29/847,546**

(22) Filed: **Jul. 26, 2022**

(30) **Foreign Application Priority Data**

Feb. 2, 2022 (EM) 008848030-0009
